UNITED STATES PATENT OFFICE.

THOMAS LARKIN, OF CUMBOLA, PENNSYLVANIA.

DESIGN FOR A HAND-DRILL.

SPECIFICATION forming part of Design No. 25,955, dated **August 18, 1896.**

Application filed July 2, 1896. Serial No. 597,906. Term of patent 14 years.

To all whom it may concern:

Be it known that I, THOMAS LARKIN, a citizen of the United States, residing at Cumbola, in the county of Schuylkill and State of Pennsylvania, have invented or produced a new and original Design for Hand-Drills for Drilling Coal, of which the following is a specification.

In the accompanying drawings, Figure 1 is an elevation of a hand drilling-tool, partly in section, to more clearly illustrate the shape thereof; and Fig. 2 is an elevation looking at the top and showing the teeth of the drill bent in the manner contemplated by my design.

In the said drawings the reference-numeral 1 indicates the body or bit of the drill, which is cylindrical in contour, and 2 indicates V-shaped projections from the upper end thereof. These projections are outwardly

bent, as illustrated in Fig. 1 of the drawings, or alternately inwardly and outwardly bent, as in Fig. 2. The numeral 3 indicates a handle which at the end meeting with the body or bit is reduced in a curved line 4, as illustrated, the line of reduction leading to the open lower end of the body or bit. 25

My design presents a hand drilling-tool of pleasant, simple, and distinctive characteristics. 30

What I claim is—

The design for a hand drilling-tool herein shown and described.

In testimony whereof I have hereunto set my hand in presence of two subscribing witnesses. 35

THOMAS LARKIN.
